VEHICLE

Kenneth P. Stanaback, 3640 Breton Road SE.,
Grand Rapids, Mich.

Filed Oct. 21, 1965, Ser. No. 87,674

Term of patent 14 years

(Cl. D90—8)

FIG. 1.

FIG. 2.

FIG. 3.

FIG. 1 is a side elevational, slightly perspective view taken from one side of the novel vehicle showing my new design;

FIG. 2 is a front view thereof; and
FIG. 3 is a rear view thereof.

The opposite side to that shown in FIG. 1 is the same as that shown in FIG. 1.

I claim:

The ornamental design for a vehicle, substantially as shown and described.
